[57] CLAIM

The ornamental design for a pitcher or similar article,
substantially as shown and described.

DESCRIPTION

FIG. 1 is a side elevational view of a pitcher or similar
article showing my new design;

FIG. 2 is a front view thereof;

FIG. 3 is a top view thereof on a reduced scale; and
FIG. 4 is a rear view thereof.

The side opposite the side shown in FIG. 1 is a mirror
image thereof.

The bottom is flat and unornamented.

Fig. 4.
